CLAIM

The ornamental design for a display screen or portion thereof with icon group, as shown and described.

DESCRIPTION

FIG. 1 depicts a front view of a display screen or portion thereof with icon group showing a first embodiment of the claimed design;

FIG. 2 is a second embodiment thereof; and,

FIG. 3 is a third embodiment thereof.

The outermost broken lines in the figures show a display screen or portion thereof, and form no part of the claimed design; all other broken lines in the figures show portions of the graphical user interface of the icon group that form no part of the claimed design.

1 Claim, 3 Drawing Sheets
